UNITED STATES PATENT OFFICE.

JOHN S. FINCH, OF BRIDGEPORT, CONNECTICUT, ASSIGNOR TO THE SINGER MANUFACTURING COMPANY, A CORPORATION OF NEW JERSEY.

POWER-TRANSMITTER.

1,387,136.

Specification of Letters Patent.

Patented Aug. 9, 1921.

Application filed July 25, 1917. Serial No. 182,654.

To all whom it may concern:

Be it known that I, JOHN S. FINCH, a citizen of the United States, residing at Bridgeport, in the county of Fairfield and State of Connecticut, have invented certain new and useful Improvements in Power-Transmitters, of which the following is a specification, reference being had therein to the accompanying drawings.

10 This invention relates to improved means for arresting the transmission of power by the application of a, so termed, dash-pot to an already existing stop-motion mechanism in such manner and having such control as 15 to give to the main or driving shaft of a machine, device or mechanism substantially such automatic control as will meet the requirements of variations in speed, as is desirable in the operating of many classes and 20 varieties of mechanical construction for effecting a sequence of like operations, as in the operating of sewing machines for effecting a seam formation or for producing predetermined figures or designs, as in button 25 sewing and eyelet and buttonhole overseaming.

Applicant is aware that it is not new to introduce into the present class of constructions the employment of a dash-pot, but it 30 is believed that it has never been employed as herein to effect a stop action which is substantially automatic in meeting the requirements of changes in speed and comprising substantially the only means employed for 35 frictionally resisting the action of the machine after the supply of power has been discontinued, in other words, as the resistance offered by the action of the dash-pot is automatically increased or diminished substantially pro rata with the changes on the speed 40 given the machine, due to the corresponding change in the speed given the piston to compress the fluid in the cylinder chamber and the latter directly connected with the main 45 shaft through a depressing member, there is effected an automatic control believed to be new to its application to stop mechanisms.

Referring to the drawings, which form a part of the specification, Figure 1 is a view 50 in front side elevation of the rear end portion of a sewing machine equipped with the present invention. Fig. 2 is a view in elevation of the stop-mechanism oscillating frame provided with a dash-pot. Fig. 3 is 55 a view in side elevation of Fig. 2 except that

the dash-pot cylinder is shown in section. Fig. 4 is a view in perspective of the piston-rod depressing cam or member.

Stop mechanisms of the general character referred to herein are well known in the art, 60 one type similar to that of the present construction being disclosed in the United States Patent to E. B. Allen, No. 743,213, dated November 3, 1903. As this invention in its present application relates to an improvement in this class of stop mechanisms, 65 only such detailed reference will be made thereto as is deemed necessary for a proper understanding of its application.

Referring to the figures, 1 represents the 70 frame-base upon which is mounted the arm bracket standard 2 and 3 the rear end portion of said bracket. 4 denotes the main or drive-shaft operatively connected by a belt 5 with one form of commonly employed 75 loop-taker actuating shaft (not shown), 6 a hand-wheel suitably secured upon said drive-shaft, 7 a loose pulley mounted upon the latter and 8 the tight or driving pulley provided with the flange 9 carrying the 80 piston-rod depressing eccentric cam or member 10.

11 represents the piston-rod oscillating frame suspended by oppositely arranged 85 pivotal screws 12 (one only of which is shown), which latter are threaded into a bracket 13 suitably secured to the standard 2. 14 denotes the piston-rod mounted in said frame for vertical movement limited in its upward stroke by the suitably secured 90 collar 15, said rod carrying at its lower end a piston 16 of a diameter slightly less than the inner diameter of the cylinder 17, the stem 18 of which is threaded into the oscillating frame bearing 19 and through which 95 passes the lower end of said piston-rod, the vents, as 20, being provided in the upper portion of the cylinder to permit the escape of the fluid.

21 represents the piston-rod spring interposed between the upper end of the stem 18 and the collar 15 and although the resiliency of said spring causes the free end 22 of the piston rod to exert a slight retardation of the depressing cam, its primary function is 100 to effect a vertical movement of the piston after the action of said cam on said free end has compressed the air in the cylinder. 105

In the present construction, as in the construction of the patent previously referred 110

to, manual means are employed for effecting the starting of the machine and means for automatically discontinuing such action which may be as shown and described in said 5 patent and as partly herein shown, or of any other approved form of control as the present invention may be employed in connection with manually controlled means only, as in stitching seams of undetermined 10 length, and, accordingly, the present reference to such combined automatic and manual control will be limited to such primary elements as are more directly connected with the stop-mechanism.

15 24 represents a rock-shaft, shown in dotted lines only, Fig. 1, provided with an arm 25 which, in the operation of the machine, is connected by means of a treadle rod 25' with a foot or other manually operated 20 treadle (not shown) and upon the rear end of said rock-shaft is suitably secured a crank-arm 26, to the free end of which is pivotally connected a stop-mechanism operating bar 27, the lower end of which is pro- 25 vided with a slot 28, shown in dotted lines only, said slotted end being pivotally connected with the frame arm 29 carried by the oscillating frame 11. 30 denotes a frame retaining arm carried by said frame whose 30 upper end is provided with a catch-lever screw 31 threaded into said retaining arm, said screw coöperating with a latch 32 carried by a catch-lever 33 suitably secured upon a shaft 34 journaled in suitable bearings (not shown) in the standard 2.

35 represents a trip-lever carried by the shaft 34 whose free end coöperates with a flange 36 of a slidably mounted sleeve 37 carried by the main shaft, said sleeve being 40 automatically controlled by common means (not shown) to move in the direction of the length of said main shaft and trip said latch out of engagement with the screw 31 and permit the spring 38 to rock the frame 45 11 and carry the free end 22 of the piston-rod in alignment with the cam-surface 23 of the cam 10, which latter, in its rotation, forces said rod downward in opposition to the resistance offered by the air being com- 50 pressed in the cylinder until the free end 22 enters the stop-notch 39 in the depressing cam, when the machine is brought to rest. It is to be understood, however, that the present invention is not limited to the par- 55 ticular form of tripping means 35 referred to, as any well known device of this nature may be employed to trip the oscillating frame 11, such a device being disclosed, for instance, in the Allen U. S. Patent No. 60 743,213, hereinbefore referred to. To start the machine the frame 11 is rocked, by actuating the pedal rod 25' previously referred to, in the opposite direction until the latch 22 engages the catch-lever screw 31, it being

understood that the driving belt (not shown) is shifted by the belt-shifter 40 from loose to tight pulley and vice versa by the rocking movements of said frame.

As the clearance between piston and cylinder is fixed it follows that the pressure of 70 the air under the piston or, in other words, resistance against its movement is proportional to the speed of the piston. In the mechanism described above the cylinder and piston form a brake for the moving mechanism and the braking power is proportional to the speed of the mechanism. The momentum of the mechanism, however, is proportional to the square of the speed, but it has been observed that in constructions of 80 the present nature the increased friction due to increased speed is such that the braking power required to bring the mechanism to a standstill is very nearly proportional to the speed of the mechanism, so that, the 85 present arrangement of piston and cylinder furnishes the kind of brake required for the given conditions.

Having thus set forth the nature of the invention, what I claim herein is:—

1. In a stop-mechanism, the combination with a driving shaft and means for rotating the same, of coöperating elements operating first in one direction for frictionally retarding the rotation of said shaft with a braking effect varying proportionally with the speed of rotation of the shaft and operating subsequently in a direction substantially transversely to said first mentioned direction to arrest the rotation of the shaft.

2. In a stop-mechanism, the combination with a rotating shaft and means for rotating the same, of a depressing member carried by said shaft, a fluid compressing dash-pot including a piston-rod, means for throwing said piston-rod into frictional engagement with said depressing member to actuate the piston-rod longitudinally and retard the rotation of the shaft with a braking effect varying substantially as the speed of rotation, and a stop-element adapted to laterally engage said piston-rod to arrest the rotation of the shaft.

3. In a stop-mechanism, the combination with a drive shaft and means for rotating the latter, of means for arresting the action of said shaft comprising a depressing member carried by said shaft, an oscillating frame, a dash-pot with its piston-rod carried by said oscillating frame, means for holding said piston-rod out of engagement with said depressing member during the normal rotation of said shaft, and means for releasing said holding means whereby said oscillating frame is locked to position said piston-rod in the path of said depressing member to frictionally retard the rotation of said driving shaft with a braking effect varying propor-

tionally with the speed of rotation, and means coacting with said piston-rod for subsequently arresting the rotation of said shaft.

4. In a stop-mechanism, the combination 5 with a drive shaft and means for rotating the latter, of means for arresting the action of said shaft including a depressing member provided with a stop-notch, a dash-pot, a piston-rod, and a piston-rod spring, said depressing member acting on said piston-rod 10 to cause the resilient action of said spring and dash-pot to retard the action of said drive shaft until the resiliency of said spring acts to set the free end of said piston-rod in 15 said notch to arrest the action of said drive-shaft.

5. In a stop-mechanism, the combination

with a drive shaft and means for rotating the latter, of means for arresting the action of said shaft including a depressing member 20 provided with a stop-notch, an oscillating frame, a dash-pot, a piston-rod, and a piston-rod spring carried by said oscillating frame, said depressing member acting on said piston-rod to cause the resilient action of 25 said spring and dash-pot to retard the action of said drive-shaft until the resiliency of said spring acts to set the free end of said piston-rod in said notch to arrest the action of said drive-shaft.

In testimony whereof, I have signed my name to this specification.

JOHN S. FINCH.
